(21) Appl. No.: **29/193,851**

The ornamental design for a reversible behind the head mount for a personal audio set, as shown and described.

(22) Filed: **Nov. 13, 2003**

DESCRIPTION

(51) LOC (7) Cl. **14-01**

FIG. 1 is a front, left, perspective view of a reversible behind the head mount for a personal audio set showing our new design in a first possible orientation such that a personal audio set mounted thereto may be worn adjacent to a wearer's left ear;

(52) U.S. Cl. **D14/223; D14/225**

FIG. 2 is a left, elevation view thereof;

(58) Field of Search **D14/188, 192,**

FIG. 3 is a front, elevation view thereof;

D14/205, 206, 223, 224; 181/129, 130;

FIG. 4 is a back, elevation view thereof;

379/430, 431, 432, 433; 381/370, 376,

FIG. 5 is a top plan view thereof;

377, 378, 379, 380, 381; D29/112; 2/410

FIG. 6 is a bottom plan view thereof; and,

(56) **References Cited**

FIG. 7 is a front, right, perspective view of the reversible behind the head mount of FIG. 1 showing a second possible orientation such that the headset mounted thereto may be worn adjacent to a wearer's right ear.

U.S. PATENT DOCUMENTS

The broken lines showing a personal audio set mounted to the reversible behind the head mount is for illustrative purpose only and forms no part of the claimed design.
